UNITED STATES PATENT OFFICE

WILLIAM H. H. DAVIS, OF SAN FRANCISCO, CALIFORNIA, ASSIGNOR TO UNITED STATES APPLIANCE CORPORATION, OF SAN FRANCISCO, CALIFORNIA, A CORPORATION OF CALIFORNIA

DESIGN FOR A CASING FOR A HAIR WAVING MACHINE

Application filed December 5, 1932. Serial No. 46,309. Term of patent 14 years.

To all whom it may concern:

Be it known that I, WILLIAM H. H. DAVIS, a citizen of the United States of America, and a resident of the city and county of San Francisco, State of California, have invented a new, original, and ornamental Design for a Casing for a Hair Waving Machine, of which the following is a specification, reference being had to the accompanying drawings, forming part thereof.

Referring to the drawings:

Figure 1 is a perspective view of the casing for a hair waving machine when not in operation, showing my new design.

Figure 2 is a perspective view of the casing as it appears in use with certain parts extended, and showing my new design.

I claim:

The ornamental design for a casing for a hair waving machine, as shown and described.

WILLIAM H. H. DAVIS.
